COMBINATION OF RESILIENT PAD AND CUTOUT INSOLE

Meyer Margolin, Elgin, Ill.

Application June 18, 1941, Serial No. 398,591

7 Claims. (Cl. 36—3)

My invention relates to a novel resilient shoe insole and more particularly my invention relates to a novel combination of insole and resilient pad, which combination is adapted to provide increased shoe comfort and a softer, more resilient cushion for the foot and increased breathing and ventilation are effected.

One of the primary functions of the insole in the shoe is to enable the assembly of the respective components of the shoe, namely upper and outsole, to facilitate the lasting of these parts.

It is the object of my invention to provide that the insole be rendered more flexible, more resilient and hence increase foot comfort. Generally I effect the increased resilience by cutting out an opening in the forepart of the insole and to increase the resilience and softness of the construction I secure over that cut out portion a resilient pad formed, for example, of rubber.

In order that the resilience of the assembly be greatest at the center portion and decrease gradually, I provide certain features of the construction which will be more specifically dealt with hereinafter. For example I may dish out the opening in the insole so that the edges of the opening are tapered, the taper extending to substantially a feather edge about the periphery of the opening. I also provide perforations not only through the resilient pad for purposes of increased ventilation, but additionally in order to provide a graduated resilience, I provide perforations in and through this tapered marginal portion of the insole, these perforations are in line with corresponding perforations extending through the resilient pad superimposed and secured thereover.

It is the object of my invention to provide a novel resilient combination of insole and resilient pad.

It is a further object of my invention to provide a combination of resilient pad and insole with increased flexibility, resilience and ventilating properties.

It is a further object of my invention to provide a novel insole adapted to provide resilient support of the foot in certain indicated areas.

It is a further object of my invention to improve the flexibility and resilience of the shoe insole.

These and further objects of my invention will become apparent from a consideration of the drawings and the specific description thereof which here follows.

Figure 1 is a central longitudinal cross section of the construction of my invention.

Figure 2 is a plan view of the resilient pad and insole of my invention.

Figure 3 is a transverse section taken along the line 3—3 of Figure 2.

Figure 4 is a central longitudinal section of a modified form of my invention taken along the line 4—4 of Figure 5.

Figure 5 is a plan view of a modified form of my invention.

Figure 6 is a section taken along the line 6—6 of Figure 7 showing a still further modified form of my invention.

Figure 7 is a plan view of a modified form of my invention shown in Figure 6.

Figure 8 is a central longitudinal cross section showing a modified form of my invention taken along the line 8—8 of Figure 9.

Figure 9 is a plan view of the form of my invention shown in Figure 8.

Figure 10 is a central longitudinal cross section of a modified form of my invention taken along the line 10—10 of Figure 11.

Figure 11 is a plan view of a modified form of my invention shown in Figure 10.

Figure 12 is a central longitudinal cross section of a still further modified form of my invention.

In Figure 1 I show a construction by means of which I provide increased shoe comfort. An outsole 10 and an insole 11 which has been split from the outsole so that an island or raised portion 12 is provided in the center forepart of the outsole, are joined after the upper 14 is lasted to the insole 11 in the usual manner. A resilient pad 15 is secured to the insole 11 by stitching 16 and 17. I may provide on the resilient pad an integral metatarsal support 19. The resilient pad 15 is provided with grooves 20 and perforations 21.

Additionally I may provide grooves 23 which communicate upwardly with the interior of the shoe by means of perforations 24. Where the perforations 21 over lie the insole 11 I may further provide perforations 26 in the insole 11 by means of which perforations I achieve two new and unexpected results. First, the insole is rendered more flexible and secondly I provide increased breathing properties for the shoe in that air is circulated through the insole and through the resilient pad and air pockets of increased depth and volume are provided by these perforations 26 in the insole 11.

It is a feature of my invention that I increase the resilience and flexibility of the insole gradually from the center ball portion outwardly towards the periphery. In the center or ball por-

tion of the insole only the resilient pad 15 lies between the foot and the outsole. As shown, I provide an opening having a tapered or skived edge 13 and through this tapered opening and the superimposed resilient pad 15 I provide perforations such as 21 which in addition to increasing the breathing property of the assembly also increases the flexibility of the combination at that point where the lamination of insole and pad first occurs. These perforations 21 minimize the stiffness of the insole so that transition from the middle of the pad 15 to the outer edge of the insole 11 is effected gradually. I may also provide perforations through the insole itself to increase the flexibility thereof.

The resilient pad 15 may extend as shown from the toe portion to the longitudinal arch or it may extend from the toe to the heel for the full length of the shoe. The resilient pad and the perforations therein together with the perforations in the insole directly below and matching the perforations in the resilient pad have great value for the increased breathing, coolness and flexibility imparted thereby.

In Figures 2 and 3 I show a plan view and cross section respectively of the construction described in detail in connection with Figure 1. It will be noted that the resilient pad 15 which has its greatest thickness in the central area tapers down to a feather edge as it approaches the marginal portion of the insole 11.

In Figure 4 I show an insole 30 having a central opening formed therein, the opening being so cut out as to provide tapered peripheral edge 31. The edge 31 tapers down from the insole thickness to a feather edge at its innermost point. Disposed over and in the opening in the insole 30 is a resilient pad 33 which may be molded or formed from a planular rubber sheet by skiving down the edges thereof to form the tapered edge 34 on the resilient pad 33. This may be effected by skiving out the resilient pad 33 from sheet form. For purposes of increased ventilation I provide perforations 35 in the resilient pad 33 and for increased breathing and ventilation effects, I may form in the pad 33, grooves 37 spaced from the perforations 35 and grooves 38 carrying perforations 39 therein.

It is a feature of this construction that increased softness in the center of the forepart of the insole is effected without impairing the strength of the insole or its constructional utility in the shoe. The resilient pad 33 may be secured to the insole 30 by the stitching 41. I effect a desirable graduated decrease of the flexibility and resilience by providing the tapered edges 34 on the filler 33 and tapered edges 31 on the insole 30, which tapered edges are superimposed over one another. To further enhance this graduated flexibility and resilience I provide perforations 43 in this portion of the insole where the tapered edges of the resilient pad are superimposed over the tapered edges of the insole. The insole is adapted to be positioned over the outsole 45. The resilient pad 33 extends over the insole and terminates in a tapered feather edge 47.

In Figure 6 I show an insole 50 having an opening in the forepart thereof, the opening being formed with a tapered edge 51. This tapered edge tapers gradually downwardly to the innermost point in the form of a feather edge. Superimposed over the opening and secured thereto by stitching 52 is a resilient pad 53 containing perforations 54, grooves 55 and combination grooves and perforations 56.

Formed integrally with the resilient pad is a portion of increased thickness forming the metatarsal 58 which is positioned within the cut out area or at that portion of the insole that is tapered down to a feather edge. This is so that the metatarsal support 58 will be located in a flexible portion of the assembly. In order to provide for the graduated flexibility and resilience described above, I provide for perforations 60 and 61 at that portion where the tapered edges of the insole and resilient pad are superimposed. The resilient pad 53 extends over a substantial area of the forepart of the insole and decreases at its periphery to a feather edge 62. The combination of resilient pad and insole are then properly attached to the outsole 63.

In Figure 8 I show a form of my invention in which the insole is made by splitting off a layer from the outsole and is formed with two openings therein, one opening lying in the center of the forepart and the other lying in the metatarsal region. More specifically an insole 70 is split off from an outsole 71 to provide a central opening designated as 72 in the forepart and a secondary opening designated as 73 formed in the region of the metatarsal arch support. Set over the insole 70 and the openings 72 and 73 is a resilient rubber pad 75 carrying an integral metatarsal arch support 76. Perforations 78 extend through the resilient pad and where the resilient pad overlies the insole 70 perforations 79 extend through both the resilient pad 75 and the insole 70. The secondary opening 73 increases the flexibility of the assembly and also increases the resilience of the construction. The resilient pad 75 is secured by suitable stitching 80 to the insole 70 and terminates along its periphery in a feather edge 82.

In Figure 10 I show a form of my invention capable of being carried out with great economy and simplicity while at the same time the major objectives of my invention are fulfilled. Thus, an insole 85 is dished out or cut out to provide a central opening 86 having a downwardly tapering edge 88. This inwardly and downwardly tapering edge 88 as will be seen increases the flexibility of the resilient pad-insole combination and also makes possible the use of a very simply formed resilient pad 90 which is made by cutting out a rubber sheet to provide the resilient pad 90 and skiving the edges to provide the tapered pad edge 91. The edge of the resilient pad 90 is tapered upwardly and outwardly to fit the tapered edge 88 of the dished out insole.

The resilient pad 90 is perforated centrally to provide perforations 93 and to increase the flexibility of the unit and graduate the flexibility from the central portion outwardly towards the periphery, I provide perforations 94 in that border portion of the combination where the resilient pad lies over the tapered edge 88 of the insole. As above, the resilient pad 90 is secured by suitable stitching 95 to the insole 85 and terminates in a feather edge near the periphery thereof and the combination resilient pad-insole is then attached to the outsole 97.

In Figure 12 I show a form of my invention in which an ordinary insole 100 is dished out to provide a primary opening 101 having tapered edges 102 in the center of the forepart of the insole and a secondary opening 104 having a tapered edge 105 in the region of the metatarsal arch support. The resilient pad 107 having tapered edges 108 is superimposed over the dished out insole 100 and secured thereto by stitching 109 to provide a

combination of resilient pad and insole. The resilient pad 107 contains perforations 111 and to provide a graduated flexibility I form perforations 112 through both the tapered edge 108 of the resilient pad and the tapered edge 102 of the opening in the insole 100. A metatarsal support 113 is formed integrally with the resilient pad 107 and this resilient pad 107 may be molded to the shape shown or may be cut out of a rubber sheet to the shape here designated.

It will be noted from the various constructions set out above which represent modified forms of my invention, the features sought are increased resilience, flexibility and ventilation. These are of paramount importance in shoe constructions of this type. The combination of resilient pad and cut out insole afford a practical and economical way for providing generally for these properties and by the constructions set forth above I enhance and properly graduate the flexibility and resilience of the unit. The novel combination of resilient pad and insole can then be utilized and lasted in the same way that the ordinary insole is used.

This application is a continuation-in-part of application Serial No. 377,948, filed February 8, 1941, for Resilient insert-insole combination.

I claim:

1. In combination, an insole and a rubber-like pad, said insole having a first opening in the forepart thereof, said opening having a tapered edge, said rubber-like pad being disposed over said opening, said rubber-like pad being tapered, said tapered portion of said rubber-like pad overlying the tapered edge of said opening, perforations in and through said tapered portion of said rubber-like pad and said tapered edge of said opening, perforations through the central portion of said rubber-like pad, a second opening in the metatarsal region of said insole and a metatarsal support contained in said rubber-like pad overlying said second opening, stitching securing said rubber-like pad to said insole, said rubber-like pad having a peripheral feather edge, said feather edge of said rubber-like pad terminating within the periphery of said insole.

2. In combination, an insole and a rubber-like pad, said insole having an opening in the central forepart portion thereof, the marginal portion of the insole surrounding said opening having a downwardly and inwardly tapered edge, said rubber-like pad being disposed over said opening, said rubber-like pad being upwardly and outwardly tapered, said upwardly tapered portion of said rubber-like pad overlying the downwardly tapered edge of said marginal portion, perforations extending through said rubber-like pad, and stitching securing said rubber-like pad to said insole, said rubber-like pad having a peripheral feather edge, said rubber-like pad extending over the untapered marginal portion of said insole but terminating within the periphery of said insole, said rubber-like pad covering almost the entire forepart of the insole.

3. In combination, an insole and a rubber-like pad, said insole having an opening in the central forepart portion thereof, the marginal portion of the insole surrounding said opening having a downwardly and inwardly tapered edge, said rubber-like pad being disposed over said opening, said rubber-like pad being upwardly and outwardly tapered, said upwardly tapered portion of said rubber-like pad overlying the downwardly tapered edge of said marginal portion, perforations in and through said tapered portion of said

rubber-like pad and said tapered edge of said marginal portion, perforations through the central portion of said rubber-like pad, and stitching securing said rubber-like pad to said insole, said rubber-like pad having a peripheral feather edge, said rubber-like pad extending over the untapered marginal portion of said insole but terminating within the periphery of said insole.

4. In combination, an insole and a rubber-like pad, said insole having an opening in the central forepart portion thereof, the marginal portion of the insole surrounding said opening having a downwardly and inwardly tapered edge, said rubber-like pad being disposed over said opening, said rubber-like pad being upwardly and outwardly tapered, said upwardly tapered portion of said rubber-like pad overlying the downwardly tapered edge of said marginal portion, perforations through the central portion of said rubber-like pad, and stitching securing said rubber-like pad to said insole, said rubber-like pad having a peripheral feather edge, said rubber-like pad extending over the untapered marginal portion of said insole but terminating within the periphery of said insole, said rubber-like pad covering almost the entire forepart of the insole, and a metatarsal support on said rubber-like pad in the region of the metatarsal arch.

5. In combination, an insole and a rubber-like pad, said insole having an opening in the central forepart portion thereof, the marginal portion of the insole surrounding said opening having a downwardly and inwardly tapered edge, said rubber-like pad being disposed over said opening, said rubber-like pad being upwardly and outwardly tapered, said upwardly tapered portion of said rubber-like pad overlying the downwardly tapered edge of said marginal portion, perforations in and through said tapered portion of said rubber-like pad and said tapered edge of said marginal portion, perforations through the central portion of said rubber-like pad, and stitching securing said rubber-like pad to said insole, said rubber-like pad having a peripheral feather edge, said rubber-like pad extending over the untapered marginal portion of said insole but terminating within the periphery of said insole, and a metatarsal support on said rubber-like pad in the region of the metatarsal arch.

6. In combination, an insole and a rubber-like pad, said insole having an opening in the central forepart portion thereof, the marginal portion of the insole surrounding said opening having a downwardly and inwardly tapered edge, said rubber-like pad being disposed over said opening, said rubber-like pad being upwardly and outwardly tapered, said upwardly tapered portion of said rubber-like pad overlying the downwardly tapered edge of said marginal portion, perforations through the central portion of said rubber-like pad, and stitching securing said rubber-like pad to said insole, said stitching extending vertically through said insole and said rubber-like pad, said rubber-like pad having a peripheral feather edge, said rubber-like pad extending over the untapered marginal portion of said insole but terminating within the periphery of said insole, said rubber-like pad covering almost the entire forepart of the insole.

7. In combination, an insole and a rubber-like pad, said insole having a first opening in the forepart thereof, said opening having a tapered edge, said rubber-like pad being disposed over said opening, said rubber-like pad being tapered, said

tapered portion of said rubber-like pad overlying the tapered edge of said opening, perforations through the central portion of said rubber-like pad, a second opening in the metatarsal region of said insole and a metatarsal support contained in said rubber-like pad overlying said second

5 opening, stitching securing said rubber-like pad to said insole, said rubber-like pad having a peripheral feather edge, said feather edge of said rubber-like pad terminating within the periphery of said insole.

MEYER MARGOLIN.
